LUMINESCENT SCREEN

Humboldt W. Leverenz, South Orange, N. J., assignor to Radio Corporation of America, a corporation of Delaware

Application January 25, 1941, Serial No. 375,906

6 Claims. (CL 250—80)

This invention relates to luminescent screens and more particularly to the method of fabricating luminescent screens suitable for use in color television systems using cathode ray tubes.

It has been proposed in connection with color television systems to utilize, at the receiving point, a cathode ray tube having a luminescent screen adapted to be bombarded by a beam of electrons to reproduce the colored image of the object transmitted. The screen is composed of a layer in which alternate lines corresponding to the cathode ray transversals luminesce blue and yellow-orange for a two-color system, instead of the ordinary screen comprising a layer of a luminescent material emitting substantially white light under bombardment. For a tri-color system the screen would be composed of different strips of luminescent material arranged in a predetermined pattern adjacent to each other, each strip luminescing with blue, green or red light. The signals received from the transmitting station would comprise three groups, the first group being generated by light from the object whose image is to be transmitted, passing through a blue filter, the second group being generated by light from the object passing through a green filter, and the third group of signals being generated by light from the object passing through a red filter.

At the receiver the cathode ray beam within the cathode ray tube would be modulated by the three groups of signals successively, the beam being advanced in a vertical direction at the conclusion of each group of signals. By making the strips of different luminescent materials narrow, the observer would perceive a color corresponding to the integrated values of blue, green and red luminescent light to give the effect of the color of the elemental area under consideration of the object transmitted, due to the persistency of vision. It will be appreciated that the strips of luminescent material must be very narrow in order to first of all provide a system having adequate resolution and definition, and secondly, to provide a reasonable size screen. My invention thus makes possible the production of such luminescent screens in a very simple, efficient manner, with reasonable ease and facility.

In accordance with my invention, a number of thin plates, such as glass, metal, mica, or plastic for example, are stacked together. The separate luminescent materials are then settled, dusted, or sprayed upon the edges of separate stacks. The plates are then separated and restacked in the desired combination. The restacked group

of plates having luminescent material on one edge is then used to "print" the luminescent screen upon a support to provide the final screen.

It will thus be appreciated that my new method of preparing luminescent screens is exceedingly simple, and provides a screen having high resolution and definition for color work as well as making possible accurate color reproduction. Accordingly, it is one of the objects of my invention to provide a new and improved composite luminescent screen for excitation by radiant energy.

Another object of my invention is to provide a method for easily producing composite luminescent screens suitable for color television reproductions.

Another object of my invention is to provide a method for forming a composite two-color luminescent screen for cathode ray receiving tubes for television systems.

Still another object of my invention is to provide a tri-color or multi-color composite luminescent screen for use in a cathode ray tube for reproducing colored television images.

Other objects of my invention will become apparent to those skilled in the art upon reading the following detailed description taken together with the drawings.

In the drawings, Figures 1a, 1b and 1c show, as a step in my new method, the individual stacks 30 of plates carrying luminescent material on their edges; Fig. 2 shows an intermediate step in my method of forming luminescent screens in which the plates have been restacked according to a predetermined order; Fig. 3 shows a further step 35 in my method of forming luminescent screens in which the alternate strips of luminescent material are "printed" on the final support surface; Fig. 4 shows schematically a screen made in accordance with my invention, while Fig. 5 shows schematically a luminescent screen made in accordance with my invention and enclosed in a cathode ray tube.

Turning now to the drawings, and assuming that a tri-color screen is to be fabricated, as an example, a plurality of thin plates 3 are stacked together to form a group 4, upon which is sprayed or settled, according to methods well known in the art, blue emitting luminescent material 5. Another stack 7 of similar plates 9 has green emitting luminescent material 11 sprayed or settled upon their edges, while the third stack 13 has red emitting luminescent material 13 affixed to the edges of the plates 15. It will be appreciated that the plates may be of any suitable material such as glass, mica, or plastic, for example.

If the plates are glass, the glass may be of the type from which microscope slides are fabricated. As is well known, the thickness of these slides can be made as thin as 0.1 mm.

The stacks 1, 7 and 13 are then separated into their individual plates 3, 9 and 15. The individual plates are then restacked sequentially in the order 3—9—15, with edges bearing the luminescent material 5, 11, 17 lying in a common plane, as shown in Fig. 2 to form a stack of which the thickness is equal to the desired height of the finished screen, and in which the individual plates alternate in sequence.

It will be appreciated, therefore, that the edges of the restacked plates will form a surface of strips of luminescent materials running in the repeated sequential order of blue, green and red.

Since the luminescent materials adhere well or firmly to the edges of the plates, the particles of luminescent material can be transferred to a suitably prepared support surface by providing a surface whose adhesive property is greater than that of the plates 3, 9 and 15.

In carrying out this step, referring to Fig. 3, the final support surface 19, such as glass, for example, has deposited thereon a binder coating of dilute alkali silicates or borates or organic binders such as nitrocellulose and alcohol or amyl acetate. With certain luminescent materials it is, of course, only necessary to moisten the glass support surface 10, with amyl acetate or water to provide sufficient adhesion. The stack or interleaved plates 3, 9 and 15 is then inverted and pressed against the binder layer 21, so that the edges bearing the luminescent material 5, 11 and 17 are in contact therewith. The luminescent material 5, 11 and 17 is thereupon transferred to the support surface 19 to form the finished screen shown in Fig. 4 in which the strips of different luminescent materials 7, 11 and 17 are affixed to the support 19 by way of the binder medium 21.

Suitable groups of materials for providing the multi-colored luminescent strips are silver-activated zinc sulfide, zinc silicate and zirconium silicate for blue; for green luminescing material, alpha-willemite activated with manganese and zinc cadmium sulfide activated with silver may be used. Red luminescing material may be chromium-activated aluminum beryllate or zinc cadmium sulfide activated by silver. It will be noted that zinc cadmium sulfide activated by silver may have its color vary from blue through yellow and green to red by merely increasing the quantity of cadmium during the processing of the material, but the use of it to produce blue light is not as desirable as other materials have greater efficiency at this end of the spectrum.

It will be understood that I have described the processing of the screen in connection with a tri-color system. Where it is desired to use a two-color system, then the alternate strips of a material may be suitably chosen from blue and yellow luminescing materials, and for the yellow luminescing material, zinc cadmium sulfide activated by silver manganese-activated beta-willemite or zinc beryllium silicate activated by manganese may be used.

It will be appreciated, of course, where a two-color system is to be provided, only two stacks of plates are necessary, but the steps in the process of settling the luminescent materials out on the edges of the stack, restacking the plates, and finally printing them on an adhesive surface upon a suitable support member, are identical with

those described above in connection with the tri-color screen.

The finished screen may then be mounted within a cathode ray tube 31 shown in Fig. 5 and the screen adapted to be bombarded by a beam of electrons 33 emitted from an electron gun 32. The beam 35 may be deflected by suitably positioned electromagnetic coils 39 and 41 positioned at right angles to each other to deflect the beam in mutually perpendicular direction. It will, of course, be understood that while electromagnetic deflecting coils have been shown, electrostatic deflecting systems positioned within the tube may be used, as is well known in the art. Furthermore, it will be appreciated that if the support member 19 is made of thin glass, then the screen may be indirectly viewed, although the screen, if formed of an opaque support member 19 may be directly viewed.

It will be further appreciated that instead of using plates, rods may be used upon which the luminescent material is settled out, and thereafter the rods restacked to provide a cross-hatch color screen of the type shown in the Zworykin Patent 1,691,324, by following the steps in the process above outlined in connection with the three-color screen.

While the screen has been described as an example in connection with excitation of cathode ray beams, it will be further appreciated that the screen may also be used for excitation by other forms of radiant energy such as ultraviolet light, X-ray, and the like.

It will be readily understood that high quality definition is easily provided by my method of forming luminescent screens for television systems. For example, in a three-color television system having 400 line definition, the total number of strips of luminescent material will be three times 400 or 1200 strips. Since glass plates may be had as thin as 0.1 mm. the height of such a screen will be 120 mm. or approximately 4½ inches high, which is not unreasonable for a projection type tube. On the other hand, if the plates are made as thick as 0.2 mm. then the two will be approximately 9½ inches, corresponding to the size screen of a 12 inch cathode ray tube used in modern television receiving sets. At the same time, my method of preparing parti-color luminescent screens overcomes the difficulties attending the preparation of screens by attempts to rule the luminescent material upon the final support surface.

Having described my invention, what I claim is:

1. The method of preparing luminescent screens which comprises the steps of forming a plurality of sets of stacked plates, coating at least one edge of said plates of each set with luminescent material, each of said sets being coated with a different luminescent material, separating the individual plates of all of said stacks, restacking said plates in accordance with a predetermined order, and transferring the luminescent material on the edges of the restacked plates to a final support surface.

2. The method of preparing a luminescent screen which comprises the steps of stacking a plurality of thin plates together, depositing a layer of luminescent material upon the edges of said stacked plates, forming a second stack of plates, depositing a second luminescent material upon the edges of said second stack of plates, forming a third stack of plates, depositing a third luminescent material upon the edges of said third stack of plates, interleaving the plates of said

first, second and third stacks, and transferring the luminescent material from said interleaved plates to a support surface.

3. The steps in the method of preparing a luminescent screen which comprises coating a support surface with a binder, stacking together a plurality of plates having luminescent material deposited on at least one edge of each plate, and impressing said luminescent material upon the binder coated on the support member.

4. The method of preparing a luminescent screen which comprises the steps of stacking a plurality of thin plates together, depositing a layer of luminescent material upon the edges of said stacked plates, forming a second stack of plates, depositing a second luminescent material upon the edges of said second stack of plates, forming a third stack of plates, depositing a third luminescent material upon the edges of said third stack of plates, interleaving according to a predetermined order the plates of said first, second and third stacks, and transferring the luminescent material from said interleaved plates to a support surface.

5. The steps in the method of preparing a luminescent screen which comprise coating a support surface with a binder, stacking together a plurality of plates having luminescent material deposited on the edges thereof, and transferring said luminescent material upon the binder coated on the support surface by impressing said edges upon the said binder.

6. The method of preparing a luminescent screen which comprises the steps of stacking a plurality of thin plates together, settling from suspension a layer of luminescent material upon the edges of said stacked plates, forming a second stack of plates, settling from suspension a second luminescent material upon the edges of said second stack of plates, forming a third stack of plates, settling from suspension a third luminescent material upon the edges of said third stack of plates, interleaving according to a predetermined order the plates of said first, second, and third stacks, and transferring the luminescent material from said interleaved plates to a support surface.
